ATTORNEYS

UNITED STATES PATENT OFFICE.

LEO L. OBERWARTH, OF FRANKFORT, KENTUCKY.

COLLAPSIBLE DRAWING BOARD.

Application filed November 14, 1921. Serial No. 514,974.

To all whom it may concern:

Be it known that I, LEO L. OBERWARTH, a citizen of the United States, and a resident of Frankfort, in the county of Franklin and State of Kentucky, have invented a new and useful Improvement in Collapsible Drawing Boards, of which the following is a full, clear, and exact description.

My invention relates to improvements in collapsible drawing boards, and it consists in the combinations, constructions, and arrangements herein described and claimed.

An object of my invention is to provide a collapsible drawing board which comprises a minimum number of parts and which can be quickly and readily assembled or disassembled.

A further object of my invention is to provide a device of the type described in which the parts are held rigidly together when assembled.

A further object of my invention is to provide a device of the character described in which the parts thereof when disassembled can be packed in a small space for transportation.

A further object of my invention is to provide a device of the type described which is simple in construction and is not likely to easily get out of order.

Other objects and advantages will appear in the following specification, and the novel features of the invention will be particularly pointed out in the appended claims.

My invention is illustrated in the accompanying drawings, forming part of this application, in which—

Figure 1 is a perspective view of the assembled board,

Figure 2 is a perspective view of the assembled board showing the underside thereof,

Figure 3 is a perspective view of the disassembled board, the parts thereof being packed in a small space, and

Figure 4 is an enlarged sectional detail of a portion of the device.

In carrying out my invention, I provide two cleats 1—1, each of the cleats having a recess 2 therein. The recess 2 extends substantially the entire length of the cleat and has beveled end walls 3. The portions 4 of the cleat 1 at each end of the recess 2 are provided with longitudinally extending grooves 5 therein. These grooves are angular in cross section, the lower surfaces there-

of lying in the same plane as the recess 2. It will thus be seen that these portions 4 are provided with walls that taper inwardly from the top thereof. The top of the board 6 is composed of three sections of material, 7, 8 and 9. The sections 7 and 9 are identical with respect to each other, each being provided with recesses 10 therein. The walls of these recesses are tapered inwardly from the top thereof and are adapted to abut the walls of the portions 4. When the sections 7 and 9 are so disposed that the portions 4 project into the recesses 10, it will be apparent that these sections cannot be moved vertically with respect to the cleats 1. The edges 11 and 12 of the sections 7 and 9 are molded so that they taper outwardly from the top thereof. The center section 8 has its edges 13 and 14 molded so as to conform with the edges 11 and 12, respectively, thus holding the sections 7 and 9 securely in place. It will be noted that the sections 7 and 9 are prevented from lateral movement with respect to the cleats 1 by means of the portions 4. The section 8 is also prevented from lateral movement by pins 15 which are carried by the cleats 1 and which project into openings in the under side of the section. As clearly shown in Figure 4, the section 8 has a metal socket 16 centrally disposed therein. The socket 16 is adapted to receive a bolt 17 which in turn pivotally secures in place a metal strip 18 for a purpose now to be described. The cleats 1 are provided on the inner sides thereof with curved grooves 19 into which the ends of the metal strip 18 are adapted to project. It will thus be apparent that the strip 18 securely holds the section 8 in place.

From the foregoing description of the various parts of the device, the operation thereof may be readily understood. In assembling the device, the sections 7 and 9 are so disposed on the cleats that the portions 4 of the cleats project into the recesses 10 of the sections 7 and 9. The section 8 is then placed between the sections 7 and 9, so that the pins 15 enter the recesses therein. It will be apparent that before the section 8 is inserted between the sections 7 and 9, the strip 18 is turned at right angles with respect to the section 8 so that the latter can be inserted between the sections 7 and 9. The strip is then rotated so that the ends thereof enter the curved grooves 19. It will be apparent that as the strip 18 is rotated

into parallelism, the section 8 will be more firmly locked in place. The board is now assembled and can be used in the same manner as an ordinary drawing board and is just as rigid and strong in construction as the boards of ordinary type.

In Figure 3, I have shown the board disassembled, the sections 7, 8, and 9 being piled one upon another and the cleats 1 being disposed thereabove. I have also shown a T-square 20 which has a head 21 hinged thereto. The T-square can therefore be disposed between the cleats 1 and be transported with the board.

15 In each of the ends of the cleats 1, I provide a bore 22 in which are adapted to be disposed drawing instruments, thumb tacks, erasers, etc. The bores 22 have covers 23 which are adapted to be disposed therein, thus effectually enclosing the contents of the bores. The cleats 1 are provided with rubber or felt pads 24 which are disposed on the under side thereof. These pads prevent the cleats from marring the surface of the article on which the board is disposed.

As heretofore stated, it will be apparent that this device is very simple in construction, that it can be quickly and readily assembled or disassembled, and can be packed into a very small space.

I claim:

1. A device of the type described comprising a board composed of three sections, the end sections having recesses in one of their sides, transverse members, each having an arcuate groove therein and projections at the ends thereof, said projections being adapted to be received in the recesses of said end sections, whereby said end sections can only be moved toward each other, and means carried by the center section and adapted to be received in said arcuate grooves for locking said section in place with respect to said transverse members.

2. A device of the type described comprising a board composed of three sections, the end sections having recesses in one of their sides, transverse members, each having an arcuate groove therein and projections at the ends thereof, said projections being adapted to be received in the recesses of

said end sections, whereby said end sections can only be moved toward each other, and means carried by the center section for locking said section in place with respect to said transverse members, said means comprising a strip pivotally secured to the center board, the ends thereof being adapted to enter the arcuate grooves in said transverse members. 55 60

3. A device of the type described comprising a board composed of three sections, the end sections having recesses in one of their sides, transverse members, each having an arcuate groove therein and a projection at the ends thereof, pins carried by said transverse members, said projections being adapted to be received in the recesses of said end sections, whereby said end sections can only be moved toward each other, and means carried by the center section for locking said section in place with respect to said transverse members, said means comprising said pins which are adapted to be received in openings in said center section, and a strip pivotally secured to the center board, the ends thereof being adapted to enter the arcuate grooves in said transverse members. 65 70 75

4. A drawing board comprising a plurality of sections capable of being assembled 80 edge to edge to provide a smooth surface, said end boards having recesses therein with tapered walls, transverse members having projections at the ends thereof and adapted to be received in said recesses, said projections having tapering walls, whereby said end boards are prevented from outward, upward, or lateral movement with respect to said transverse members, the contacting edges of said boards being fashioned so as to hold each other in the same plane, said transverse members having arcuate-shaped grooves, means for preventing lateral movement of the central board with respect to said transverse members, a spring strip operatively carried by said central board, said arcuate-shaped grooves being adapted to receive the ends of said strip and to flex said strip so as to hold said central board in place, whereby said drawing board can be readily assembled or disassembled without the aid of tools. 85 90 95 100

LEO L. OBERWARTH.
